UNITED STATES PATENT OFFICE.

IRA D. HURLBUT, OF PRAIRIE DU CHIEN, WISCONSIN.

ADDRESSING-MACHINE.

SPECIFICATION forming part of Letters Patent No. 356,130, dated January 18, 1887.

Application filed April 15, 1886. Serial No. 198,984. (No model.)

To all whom it may concern:

Be it known that I, IRA D. HURLBUT, a citizen of the United States of America, residing at Prairie du Chien, in the county of Crawford and State of Wisconsin, have invented certain new and useful Improvements in Addressing-Machines, of which the following is a specification, reference being had therein to the accompanying drawings.

10 My invention relates to that class of machines which are used for addressing papers, circulars, &c.; and it consists in an improved construction by which the operator is enabled to address papers and envelopes with rapidity and accuracy.

15 In the accompanying drawings, Figure 1 is a perspective view of my improved machine mounted on a galley-cabinet. Fig. 2 shows in part the same in vertical section. Fig. 3 is a plan view of same. Fig. 4 shows in section the bed-plate, circular disk, and galley detached. Fig. 5 represents one of the printing-plates, and shows the manner of attaching same to galley.

20 A designates the bed-plate, which forms the foundation on which is centrally pivoted a circular disk, B, having the notches *a* in its periphery and provided with the ratchet-teeth *c* on its upper face at its periphery.

25 C indicates a galley, formed of a circular plate of metal, corresponding in size with the inner circle of the ratchet-teeth *c*. The galley has formed on or attached to its face the clamps or seats *c'*, arranged along its periphery, in which are removably placed the beveled printing-plates *d*, each bearing the name or address of a party to whom a paper or circular is to be addressed. The galley is removably secured to the surface of the ratchet-disk B,

30 usually by means of fixed pins or studs *f* on the disk and holes *g* in the galley-plate. A number of galleys, C, are provided, each of which holds a certain number of printing-plates, *d*, and when the addresses on one galley have been printed it is readily removed and another, bearing plates with other addresses, is substituted.

35 D indicates a bar, the inner end of which is loosely connected with the axis or pivot *h* of the disk B, the bed-plate being recessed at *m* to receive and allow the movement of said bar,

which extends outward to the periphery of the disk. To the outer end of the bar D is fastened a pawl or dog, *n*, which rests on and is formed to engage with the teeth *c*. 55

E is a vertical stamping-bar, which carries a stamp-head, *p*, said bar being loosely secured in position to hold the stamp-head so that the printing-plates *d*, when the machine is in operation, will pass successively under the head. 60 After bar E has been brought down to print an address it is raised again by a spring, *q*. The said stamping-bar is connected by rod or piece *r* with the pawl *n*, the parts being so constructed that when the bar E is brought down 65 the pawl *n* is drawn the width of one tooth *c*, and engages with it as the spring raises the bar, pushing it forward and causing the disk B to turn the distance necessary to bring the next plate *d* under the stamp-head *p*. 70

A spring-catch, *s*, is secured in position to engage with disk B in the notches *a*, the catch and notches being so formed as to allow the rotative movement of the disk caused by the movement of the pawl *n*. 75

It will be seen that the plates *d* are arranged on the galley so that one plate is in line with each tooth *c*, and after each downward stroke of the stamp-head the disk B is turned one tooth forward, and consequently the plate *d* 80 makes a like movement, bringing the next plate *d* under the stamp-head.

The machine is mounted on the top of a cabinet, G, suitably constructed and provided with shelves *u* to receive a number of galleys filled 85 with plates *d*, and when the addresses on one galley have been printed it is taken from the disk B and another is drawn from the cabinet and placed on the disk, when the printing may be continued as before. 90

H indicates a foot-treadle, by means of which the stamping-bar is operated.

The machine is automatic and accurate in registering, simple in construction, and not liable to get out of order. 95

The printing-plates may be inked by any suitable inking devices.

I claim—

1. In an addressing-machine, a horizontal rotative disk carrying a removable galley provided with printing-plates, in combination with a spring stamping-bar and means con-

nected with said bar for rotating the disk and galley, substantially as and for the purposes described.

2. In combination with a circular galley having devices for holding printing-plates, a pivoted circular disk, B, provided with ratchet-teeth, a pawl carried by a bar, E, loosely connected with the pivot of the circular disk, and a spring stamping-bar connected with and actuating the pawl, substantially as and for the purposes set forth.

3. In combination with pivoted circular disk B, provided with notches *a* and teeth *c*,

the removable circular galley C, spring-catch *s*, vertical spring stamping-bar provided with head *p*, pawl *n*, carried by pivoted bar E and connected with the spring stamping-bar, and a bed-plate, substantially as set forth and described. 15

In testimony whereof I have affixed my signature in presence of two witnesses.

IRA D. HURLBUT.
